UNITED STATES PATENT OFFICE

AXEL WASBERG AND KENNETH J. TOBIN, OF CHICAGO, ILLINOIS, ASSIGNOR TO CAMEL COMPANY, OF CHICAGO, ILLINOIS, A CORPORATION OF ILLINOIS

OPENING, CLOSING, AND LATCHING MECHANISM

Application filed September 27, 1928. Serial No. 303,691.

This invention relates to door opening, closing and latching means, and concerns itself with mechanism for swinging the latching bar of the door and securing the same in closed position.

5 The invention comprises the novel structure and combination of parts hereinafter described and more particularly pointed out and defined in the appended claims.

10 In the accompanying drawings which illustrate a preferred embodiment of this invention, and in which similar reference numerals refer to similar features in the different views:

15 Figure 1 is a fragmentary end elevational view of a house car having a door with a latching bar controlled in accordance with this invention.

20 Figure 2 is a fragmentary end elevational view showing the parts in a different position.

Figure 3 is an enlarged fragmentary end elevational view taken adjacent the corner of the car.

25 Figure 4 is an enlarged sectional view taken upon the line IV—IV of Figure 3.

As shown on the drawings:

In the drawings there is shown a part of the end of a house car embodying a door 1 hinged to an end wall of the car by 30 hinges 2. A casting 3 is secured to the door, a second casting 4 is pivoted to the casting 3 and a latching bar 5 is rigidly secured to the casting 4. The latching bar which is 35 swingable upon the pivot 6 of the two castings is provided with an upper casting 7 and a lower casting 8. Each casting 7 and 8 has a projecting lip or flange 9. Upon the upper and lower parts of the car are 40 oppositely facing keepers 10 and 11. Each keeper has a flaring wall 12 which draws the ends of the latching bar 5 inwardly. The flanges 12 are provided with overhanging lips 13 under which the lips or flanges 45 9 on the castings 7 and 8 engage, whereby the top and bottom of the car are tied together.

Upon the lower end of the door, there is secured a casting 14 upon which a hook-shaped lever 15 is pivoted as indicated at

16. It will be noted that the lever 15 is pivotally secured at one end and has an upwardly extending hook-shaped end 15a rising above the pivot. Upon the latching bar 5, there is a casting 5a having a shoulder 5b adjacent which there is pivoted a hook 17 with which the hook-shaped end 15a of the lever 15 is adapted to cooperate. The outer periphery 15b (Figure 3), of the hook-shaped end 15a is in the form of a cam for a purpose that will later appear.

The lower casting 8 on the latching bar 5 is provided with a sheath 18 through which a latching bolt 19 extends. This latching bolt 19 extends through an aperture in the bottom of the keeper 11 and thuswise locks the latching bar 5 when in latching position against swinging movements. It will be noted that the lower end of the locking pin 19 is provided with a slope 20 whereby, when the bar is swung from the position shown in Figure 2 to the position shown in Figure 1, this sloping end will strike the keeper and be elevated and will travel along upon the base of the keeper until it registers with the aperture therein when it will automatically drop therein by gravity and latch the bar 5 in its operative position. The pin 19 must be manually elevated when it is desired to swing the bar 5 in inoperative position.

The sheath 18 and pin 19 are provided with registering apertures 21 for receiving a sealing wire 22 for securing the door against unauthorized opening.

Assuming that the door is in closed position as shown in Figure 2 with the latching bar 5 in inoperative position, and it is desired to draw the bar 5 to its operative position. To do this, the hooked end of the lever 15 is engaged with the hook 17 and the lever is then swung downwardly, the pin 19 riding over the base of the keeper and automatically dropping by gravity into its latching aperture when the rod 5 has been swung to its operative position. Now if it is desired to swing the bar 5 in the opposite direction, the pin 19 is manually elevated and the lever 15 is elevated to bring the cam surface 15b against the casting 5a. This

cam surface will act against the casting 5a as the lever 15 is elevated and swing the bar outwardly. It will, of course, be understood that the ends of the bar 5 are usually wedged in under the keepers and considerable force is required to initially swing the bar 5 from its operative position. The lever 15 readily produces this initial movement of the bar.

10 We are aware that many changes may be made and numerous details of construction may be varied through a wide range without departing from the principles of this invention, and we, therefore, do not propose 15 limiting the patent granted hereon, otherwise than necessitated by the prior art.

We claim as our invention:

1. In a house car, a hinged door, keepers above and below said door, a latch bar pivoted upon said door and engageable under said keepers, a hook upon the lower end of said bar and a cam lever having a hooked portion for engaging said hook for drawing the lower end of the bar in one direction 25 and a cam portion for forcing said bar in the other direction.

2. In a house car, a hinged door, keepers above and below said door, a latch bar pivoted upon said door and swingable under 30 said keepers, a hook upon the lower end of said bar, a lever pivoted to said car and having a hooked portion for engaging said hook and swinging said bar to its operative position, said lower keeper having an aperture 35 and a latching member slidably carried by said bar and movable into said aperture when said bar is in operative position.

3. In a house car having a hinged door, keepers above and below said door, a swingable latch bar upon said door for engaging under said keepers, cooperating means on said car and door for drawing said bar to its operative position, and means automatically operated when said latch bar is in operative position for latching the same against movement.

4. In a house car having a hinged door, keepers above and below said door, a latch bar pivoted to said door and swingable under 50 said keepers, and a latching member carried by said bar and movable into latching engagement with the lower keeper when said bar is in its operative position.

5. In a house car having a hinged door, keepers above and below said door, a latch bar pivoted to said door and swingable under 55 said keepers, a hook upon said bar and a lever pivoted upon said car and having a hooked portion for engaging said hook and moving said bar to operative position, and latching means carried by said bar and movable into engagement with the lower keeper when 60 said latch bar has been moved to operative position for latching the same against movement.

In testimony whereof, we have hereunto subscribed our names at Chicago, Cook County, Illinois.

AXEL WASBERG.
KENNETH J. TOBIN.
